UNITED STATES PATENT OFFICE.

LOUIS S. AURIÈMA, OF ATHENS, GREECE.

WATCH.

1,259,198.

Specification of Letters Patent. Patented Mar. 12, 1918.

Original application filed September 3, 1913, Serial No. 788,024. Divided and this application filed February 28, 1916. Serial No. 20,854.

To all whom it may concern:

Be it known that I, LOUIS S. AURIÈMA, a subject of the King of Greece, residing at Athens, Greece, have invented certain new 5 and useful Improvements in Watches, of which the following is a full, clear, and exact description.

This invention relates to watches and more particularly to the mounting which 10 supports the dial in place upon the movement.

The object of the invention is to protect the dial against injuries resulting from the shocks or jars to which the dial is subjected when the watch is dropped or otherwise carelessly handled, for, as is well known, the face of the dial which carries the numerals indicating the divisions of time is coated with a layer of enamel or some other 20 fragile substance which is easily cracked or chipped.

With this object in view, the invention consists of a resilient mounting for the dial which supports it upon the movement. 25 Preferably this resilient mounting is so constructed that the dial is supported in spaced relation to the front face plate of the movement and is designed to permit the independent movement of the dial in all directions. In the specific embodiment of the 30 invention shown, this is accomplished by a spring finger projecting from the rear face of the dial which is suitably secured to the front face plate of the watch movement.

35 Referring to the drawings;

Figure 1 shows in elevation a watch having its dial mounted in accordance with the principles of my invention;

Fig. 2 is a central section through such 40 a watch with the casing removed;

Fig. 3 is a detail showing a rear elevation of the improved form of dial; and

Fig. 4 is a front elevation of the watch movement showing the means for securing 45 the dial to the same.

The improved form of mounting is adapted to be used in conjunction with any standard make of watch, but the type of watch shown is one which has been designed to 50 protect various other parts of the watch movement and casing from injury and is shown and described in my application Serial No. 788,024, filed September 3, 1913, of which application the present case is a

division; the watch case comprising a casing 1 which is provided with shock absorbing devices 2 consisting of segmental shaped parts resiliently mounted in the casing. An open face watch is illustrated and disposed at the rear of the watch crystal is a dial 3. 55 This dial is shown in section in Fig. 2 and consists of a thin metallic disk 4. The disk 4 is coated with a layer of enamel or other fragile material 5 upon which are printed the numerals indicating the division of time. 60 As is obvious, the coating 5 is easily cracked or chipped when the watch is roughly handled and to prevent this, the dial is mounted in the manner which will now be described. 65

Surrounding the peripheral edge of the dial is a rim 6 which carries a resilient finger 7 projecting radially toward the center of the disk. This finger extends over the rear face of the dial and is offset laterally therefrom as at 8. The watch movement is of the usual construction and consists of the plates 9 and 10 which are joined together by posts or pillars 11, 12, etc., the gears and other portions of the movement being 70 incased between these plates. The free end of the offset finger 7 is secured to the front face plate 9 of the movement so that the dial is spaced from this plate a sufficient distance to permit an independent movement 75 of the dial in all directions. One way in which this may be accomplished is by providing a post 12' having a slot therein into which the free end of the finger fits where it is securely held by a set screw 14. The 80 post may be mounted on the plate in any desired manner and in the form shown the shank of the post passes through the plate and has an offset end 15 which engages an offset on the pillar 12. The dial is 85 provided with a central aperture or opening 16 through which the shafts 17, which carry the hands 18 of the watch, project, which opening is made sufficiently large to insure that the surrounding edge or wall will not 90 engage the shafts 17 when the dial is moved relatively to the watch movement. The 95 resilient finger 7 described is of sufficient resiliency to permit the dial to have a slight movement independent of the works in all 100 directions, and should the watch be dropped, the resilient finger 7 will take up the force 105 of the impact of the blow which would oth-

erwise be transmitted to the dial itself and cause the dial to be cracked, chipped or otherwise injured.

Claims:

5. 1. In a watch, a movement including a front face plate, a dial, a rim surrounding the dial, and resilient means connecting the rim to the front face plate of the movement and holding the dial in spaced relation to the movement.
10. 2. In a watch, a movement having a front face plate, a dial, a resilient finger projecting from the rear face of the dial, and means carried by the front face of said movement for securing the free end of said finger to said front face plate, said finger extending substantially radially inwardly
- 15.

toward the center of the dial and having a portion thereof offset, whereby said dial is maintained in spaced relation to the front 20 plate of said movement.

3. In a watch, a movement, a dial, a post carried by the front face plate of said movement, said post having a slot therein, and a resilient finger carried by said dial having 25 its free end secured in said slot.

4. In a watch, a movement, a dial, a rim surrounding the dial, a resilient finger carried by the rim, and means for securing the free end of the finger to the movement. 30

In witness whereof I subscribe my signature.

LOUIS S. AURIÈMA.
